A. N. MUMMERT.

DUST COLLECTING BAG FOR VACUUM CLEANERS,
APPLICATION FILED AUG. 6, 1913. RENEWED DEC. 15, 1915.

1,184,485.

Patented May 23, 1916.

UNITED STATES PATENT OFFICE.

ALICE N. MUMMERT, OF GOSHEN, INDIANA.

DUST-COLLECTING BAG FOR VACUUM-CLEANERS.

1,184,485.

Specification of Letters Patent. Patented May 23, 1916.

Application filed August 6, 1913, Serial No. 783,281. Renewed December 15, 1915. Serial No. 67,082.

To all whom it may concern:

Be it known that I, ALICE N. MUMMERT, a citizen of the United States, and a resident of Goshen, in the county of Elkhart 5 and State of Indiana, have invented a new and Improved Dust-Collecting Bag for Vacuum-Cleaners, of which the following is a full, clear, and exact description.

This invention relates to new and improved dust collecting bags for vacuum cleaners, and more particularly to an improved bag for this purpose which is constructed of a single blank section of paper or cloth capable of convenient attachment 15 to and removal from a vacuum cleaning machine, the device being so inexpensively constructed that after it has been filled with dust and sweepings it may be destroyed or burned with the latter, thus obviating the 20 necessity of coming in contact with or inhaling the dust and dirt.

In connection with electric or other vacuum cleaners as now generally constructed, it is common to use a cloth bag which 25 catches the dirt from the discharge of the blower casing, and these bags are so expensively constructed that they must be removed and emptied when full, to permit continued operation of the cleaner, resulting 30 in considerable inconvenience both in the disagreeable manner in which the bag must be removed or attached, as well as causing considerable annoyance by coming in contact with the dust and disease laden 35 germs on account of it being necessary to empty the receptacles.

The present invention is designed to overcome these defects and objections, and further embraces a novel bag or pouch construction 40 having an inlet portion or tube formed integrally with the blank and directed or disposed within the area of the bag for discharging the dust therein and preventing the escape of the latter until the 45 bag has become full, while novel and inexpensive means are also provided for removably securing the bag to the discharge member of the cleaner and to the handle thereof, whereby the bag may be conveniently removed and a new one substituted.

With the above and other objects in view, the invention resides more particularly in the peculiar combination and arrangement 50 of parts which will be illustrated as a preferred embodiment in the accompanying drawings and described in the specification.

Reference is to be had to the accompanying drawings forming a part of this specification, in which similar characters of reference indicate corresponding parts in all 60 the views and in which—

Figure 1 is a side elevation of my improved dust collecting bag attached to a well known form of pneumatic carpet sweeper; Fig. 2 is a vertical sectional view 65 of the bag slightly enlarged with respect to that shown in Fig. 1; Fig. 3 is a plan view of the blank from which the bag is constructed; and Fig. 4 is a horizontal sectional view of the improved bag taken on 70 the line 4—4 of Fig. 2.

In the illustrated embodiment of the invention, the numeral 10 indicates the motor casing of an ordinary vacuum cleaner having the mouth or suction piece 11 and an 75 outlet or discharge member 12, there also being a handle 13 which is pivoted or otherwise attached to the motor casing containing the usual blower or suction fan, whereby the machine may be advanced across the floor 80 or otherwise conveniently handled. This structure is used to show the practical use and application of the invention, of which it forms no particular part, as the device 85 may be applied to various machines of the vacuum type to which bags can be attached for catching the dirt and sweepings.

The bag proper is indicated by the numeral 14, the same consisting of a single blank section of material, either paper or cloth, of such texture that dust and sweepings will readily adhere to it, as for instance, canton flannel or crêpe paper, the latter of which is illustrated in Fig. 4 of the drawings. The blank from which the bag 90 or pouch is constructed is substantially fish shape or egg shape, except that the top portion thereof is severed to provide oppositely sloping edges 15, while the bottom portion thereof is provided with a fish tail 95 extension 16 of reduced width relative to the width of the blank, whereby when the blank is folded vertically it will take the form of a semi-egg shaped bag or pouch, as shown in Figs. 1 and 2 of the drawings. The blank to one side of its horizontal center, referring to the position shown in Fig. 3 of the drawings, is slightly wider than the opposite side, so that when the blank is folded as described the extended part indicated by the numeral 17 is re-bent or folded 100 over the edge 18 at the opposite side of the

blank and stitched thereto, as shown at 19, so that the bag is considerably strengthened for all desirable purposes, whether constructed of cloth or paper.

- 5 The upper edge of the blank is folded, as shown at 20, and stitched as shown at 21 to provide a hem for reinforcing the open upper end of the bag or pouch, whereby it may be suitably held by a clamp 22 and 70 supported from the handle as by means of a flexible connection 23. The extension 16 has its vertical edges stitched together, as shown at 24, and the inlet portion or tube thus provided is turned into the bag proper 10 in the manner shown in Fig. 2 of the drawings, it being observed that the tapered formation of the extension causes it to be enlarged upwardly toward its free end to 15 permit the unobstructed escape of the dust, 20 dirt and sweepings into the bag.

To attach the bag to the discharge member 12, a section of cord or tape 25 is stitched to the bag, preferably by means of the stitching 19, and after the reduced portion or extension of the bag is slipped over the discharge member in the manner shown in Fig. 1 of the drawings, such fastening means is tied there-around, thus permitting convenient attachment and removal of the bag. It will 25 also be observed that considerable space is provided around the tube 24 in which the dust and dirt are received, so that it is obvious that when the bags are made of considerable size they may be used for a considerable length of time, and may be destroyed or burned to obviate the inconvenience of coming in contact with or inhaling the dust and sweepings. By this means extremely sanitary conditions are provided for 30 and the value of vacuum cleaners for universal use greatly enhanced.

The bag may be used separately in the manner described, or secured in any of the outer bags or compartments commonly used 45 with dust collectors or vacuum sweepers, and removed to be destroyed or burned with the sweepings and another bag inserted. Also, by reason of the peculiar construction or shape of the bag, increased area is provided 50 within the bag at the bottom and around the inlet tube for the collecting and holding of a large amount of dust and sweepings without permitting the return thereof to the cleaner.

55 Having thus described my invention, what I claim as new and desire to secure by Letters Patent is:—

- 60 1. A dust collecting bag for vacuum cleaners, comprising a body having a straight forward edge, a curved rearward edge and a reduced integral bottom extension forming a tube said tube being turned into the bag to be adjacent the straight forward edge to 105 form a surrounding storage space.

65 2. A destructible dust collecting bag for a

vacuum cleaner having a discharge member, comprising an inclosure, said bag having an abruptly restricted portion providing a bottom pouch and a discharge tube designed to fit the discharge member of the cleaner, said 70 bag being constructed of such material as to cause dust and sweepings to adhere to the interior surface thereof, said bag comprising a single fish-shaped blank folded upon itself and having its free end portions secured together to provide upper and lower openings. 75

3. A dust collecting bag for vacuum cleaners, comprising a body having a reduced integral bottom extension forming a tube, said tube being turned into the body to form a 80 pouch surrounding the tube whereby return of the heavy particles to the cleaner is prevented.

4. A bag of the class described, comprising a blank section of material having its top 85 portion severed and its lower portion provided with a fish tail extension, said blank being folded upon itself and having its free edges stitched together to produce open ends, the extension producing a tapering tube, said 90 tube being folded into the area of the bag.

5. A bag of the class described, comprising a blank section of material having its top portion severed and its lower portion provided with a fish tail extension, said blank 95 being folded upon itself and having its free edges stitched together with the ends open, the extension producing a tapering tube, said tube being folded into the area of the bag, and means attached to the bag adjacent 100 said tube for securing the same to the discharge member of a vacuum cleaner.

6. A bag of the class described, comprising a blank section of material having its top portion severed and its lower portion provided with a fish tail extension, said blank 105 being folded upon itself and having its free edges stitched together to form open ends, the extension producing a tapering tube, said tube being folded into the area of the 110 bag, the top edge of the bag being hemmed, and a tape stitched to the bag near its lower edge for engagement around the tube whereby the latter may be attached to a vacuum cleaner.

115 7. A dust collecting bag for vacuum cleaners, having a portion thereof designed to fit the discharge member of the cleaner, said bag being of a texture to cause dust and sweepings to adhere to the interior surface 120 thereof and comprising a single blank of substantially egg shape in plan with its top portion severed at opposed angles to the center of the blank and its bottom portion provided with a reduced integral extension, 125 the blank being folded vertically substantially intermediately of its width to produce a curved bottom portion and a rectilinear top portion, and the free edges secured together to form a dust-proof joint at the bot- 130

tom, said reduced portion forming a tube extending into the bag.

8. A blank for forming a dust bag for vacuum cleaners, consisting of a substantially fish-shaped piece of material having its top portion cut off to form oppositely sloping edges.

In testimony whereof I have signed my name to this specification in the presence of two subscribing witnesses.
